JOHN F. MARTIN, OF SPRINGFIELD, MASSACHUSETTS, ASSIGNOR TO UNITED AMERICAN BOSCH CORPORATION, OF SPRINGFIELD, MASSACHUSETTS, A CORPORATION OF NEW YORK

IGNITION TIMER

Application filed August 27, 1932. Serial No. 630,664.

My invention relates to improvements in timers; particularly timers for the ignition circuits of internal combustion engines, comprising a circuit interrupter for low tension current and a high tension distributor to control the flow of current to the spark plugs of the ignition system.

An object of the invention is to provide a combined timer and ignition coil of such construction that the parts of the timer are enclosed in a suitable housing on which the ignition coil can be mounted; and of such design that the various parts are rendered accessible for inspection and repairs.

Another object of the invention is to provide a timer of simple, compact, inexpensive and durable construction which is certain and efficient in operation, easy to assemble and take apart when examination or repairs is needed and capable of being readily lubricated and kept in proper condition for operation when in service.

Other objects will be set out in the following description taken in combination with the drawings on which I show an embodiment of the invention. The disclosure, however, is illustrative only and I may make changes in the shape, size and arrangement of the various parts without going beyond the scope and spirit of the invention.

On the drawings:

Fig. 1 is a longitudinal section through a timer according to my invention;

Fig. 2 is a transverse section on the line 35 2—2 of Fig. 1;

Fig. 3 is a view showing in elevation the plate supporting the interrupter contacts with the wall of the casing in transverse section;

Fig. 4 is a front elevation of the timer;

Fig. 5 is a top elevation thereof;

Fig. 6 is a front elevation of the rotary element of the distributor; and

Fig. 7 is an inside elevation of one of the stationary members of the distributor supported by the terminals to be connected by high tension wires to the spark plugs.

On the drawings the same numerals identify the same parts throughout.

The numeral 1 indicates a housing or cas-

ing of metal for the parts of the circuit interrupter and distributor of the timer; this casing being adapted to be secured in stationary position on the outside of the framework of the engine for which it is intended. In this casing rotates an operating shaft 2 connected to one of the shafts of the engine in any suitable manner. The top of the casing has an opening 3 which is closed by a cover of insulation 4 which serves as a base plate for the housing 5 of a high tension ignition coil and cooperates with the timer. In the casing 1 the rotary member of the distributor is shown at 6 and between this rotor and the plate 8 which carries the contacts of the interrupter 55 is a centrifugal governor 7. The cover 4 may be provided with packing 9 between it and the top of the casing 1 to make a good joint. The rotor 6 is disposed on the shaft 2 adjacent the rear end of the casing 1 while 60 the parts of the circuit interrupter are mounted in the front of the casing to render them more accessible. The governor 7 is between the rotor and the circuit breaker and can easily be gotten at by the removal of the 65 timer plate 8.

Within the housing 5 is a magnetic core 10 made up of a bundle of wires and surrounding this core is the primary winding 11. This winding is enveloped in a sleeve 12 of insulation in the top of which is a closure ring 13 which fills the space between the sleeve 12 and the core 10. The secondary may be in two sections 14 wound over the sleeve 12. The core 10 may rest upon an insulating disc 80 15 in a recess on the top of the cover plate; and said recess may receive also the lower end of the sleeve 12. Secured to the lower or inner face of the cover plate 4 is an angle-shaped conductor element 16 which may be joined by pins 17 to one of the terminals of the primary coil 11.

The plate 4 receives pieces of tubing 18 and 19 which are molded fast in the housing 5 and project into bores provided in the plate 95 4. This housing is thus made fast to the plate 4, because the lower ends of the tubing are spun over to make a riveted joint with the plate, and thus the plate and housing are secured together. The piece of tubing 19 is 100

made longer and projects downward into a boss 20 that extends into the casing 1 through the opening 3 and has in its lower end a contact brush 21 normally forced outward by a spring 22. The rotor is hollow at one end to fit around a bearing 23 at the rear of the casing 1, and this rotor may have a pair of flanges 24 and 25 between which is a slip ring 26 which makes contact with the brush 21. 5 This brush will be secured to one terminal of the secondary windings of the coil, the other terminal being grounded, and the flanges 24 and 25 will have conductor arms 27 and 28 respectively spaced a suitable number of angular degrees apart to come into operative position by turns with the distributor terminals to be described later, insulatably supported in the side of the casing 1. 10 The front end of the shaft 2 is supported in another bearing 29 at the center of a cap 30 which closes the front of the casing 1. The inside of this casing at the front has an annular shoulder 31 against which the interrupter plate 8 abuts and the cap 30 fits against 15 the outer face of this plate around the circumference. The conductor element 16 extends down behind this plate and is joined thereto by a spring 32 which presses against the rear of the plate. This spring is secured 20 to the element 16 by a screw 33. A projection or tongue 34 is struck up from the plate and bent outward and is perforated to carry a screw 35, the end of which carries the fixed contact of the interrupter. A lever 36 of insulation is mounted on a pivot 37 on the plate 8 and attached to this interrupter lever is a spring 38 carrying the movable contact of the interrupter, this spring 38 being anchored to an insulated projection 39 on the plate 8. The 25 other terminal of the primary will be connected to the spring 39. On the adjacent end of the shaft 2 is a cam member 40 adapted to engage the end of the interrupter lever 36 periodically and move it to separate the contact 35 and that on the spring 38. 30 The terminals of the primary coil 11 are united one to the spring 38, and the other to the contact element 35, and one of these parts must of course be insulatably mounted 35 on the plate 8. 40 The governor between the circuit interrupter and the distributor rotor 6 comprises a plate 41 rigid with the rotor and the shaft 2. Surrounding the shaft in front of this 45 plate 41 is a spacing sleeve 42 which separates the plate 40 from a second plate 43. Governor weights indicated at 44 are mounted on one or more pivots 45 affixed to the plate 43. These governor weights have studs 46 which 50 engage slots 47 in the plate 41 and they also have studs 48 which pass through openings 49 in the plate 43 to engage springs 50 which are affixed to the upturned ends 51 of a plate 52 by means of suitable screws. The plate 52 55 may be affixed to the plate 43 by screws or

other suitable means. Made rigid with the plate 43 is a sleeve 53 that carries the cam 40 and this cam sleeve may have a collar 54 which is tightly gripped by the plates 43 and 52 so that the cam and the governor plates 43 and 52 are firmly connected. Obviously whenever the speed rises the governor weights will fly outward and shift the plates 41 and 43 with respect to each other. This movement of the weights being resisted by the springs 50. The slots 49 may have any suitable shape. 70 75

The plate 8 has an opening 55 adjacent the screw 33 to permit this screw to be removed and the plate 8 taken out. At this lower side, the cap 30 has an opening 56 and at 57 is a cover for the cap 30, this cover being held in place by a suitable element 58 which may be a bail having its ends pivoted in openings in the sides of the casing. The rim of the cover 80 engages a shoulder 59 around the outside of the cap 30 and the bail 58 thus holds plate 8, cap 30 and cover 57 in place. 85

The opposite sides of the casing 1 adjacent the rotor 6 have openings to receive plates of insulation 60 each of which carries distributor terminals 61 in two pairs, one pair being in the transverse plane of the flange 25 and the other in the plane of the flange 24. The four terminals in each transverse plane are 90 spaced equidistantly apart. The rotor terminals 25 and 27 are about half as far apart as the terminals of each pair. Hence the arms 27 and 28 will close the circuit alternately to the different sparkplugs of the engine. The members 60 can be removed at will to inspect the terminals 61. 95 100

In the rear of the casing is a hollow duct 63 having an inlet element 64, and surrounding the adjacent end of the shaft 2 is a bushing 62, the lower end of the bore 63 terminating in a chamber 65 to receive lubricant. The bore 63 continues through the lower half of the casing where it contains a piece of wicking 66 held by a spring 67 against the shaft 2. The bottom of this duct is closed by a plug 68. In the cap 30 in the front of the casing is a bearing 69 for the front end of the shaft 2. 105 110 115

As the shaft 2 rotates the primary circuit will be broken as many times in each revolution as there are terminals 61 and the distributor arms 27 and 28 will close the circuit to the distributor terminals 61 in two transverse plates thereof by turns. It will be noted that all of the connections from the coil to the timer are made through the plate 4 and are enclosed in the housing. The rotor is at the rear of the casing because it seldom requires attention, while the circuit breaker points are in front where they can easily be inspected and kept in condition by taking off cover 57. The plate 8 may have a hole large enough to permit the removal by slipping it over the cam 40 so as to give access to the 120 125 130 135

governor 7. The entire construction is thus very practical and can very easily be kept in working order.

The plates 60 carrying the fixed terminals 5 61 of the distributor have outside covers 79 held in place by bail members 70 mounted and operating in the same way as the bail member 58. Each cover 79 has a hollow neck 71 through which the high tension leads are 10 passed into the covers. Also the side of the casing has a boss 72, the outer end of which may have a packing gland 73 for certain connections to the governor, not shown, and not part of this invention and capable of being 15 dispensed with in case the timer is to be operated without such parts. At 74 is a condenser mounted on a metallic support 75 at the side of the cap-plate 4 and connected by said support to one terminal of the primary 20 and the other terminal of the condenser may be grounded. Said terminal of the primary will, of course, be connected to one of the contacts of the interrupter mounted on the plate 8, and the condenser 74 will, of course, be in parallel with the terminals of 25 the interrupter. The other terminal of the primary will be connected by a conductor to a suitable source of current not shown in the drawings.

30 Having described the invention, what is claimed is:

1. A timer casing adapted to be secured to the frame of an internal combustion engine to control the ignition circuits, said casing having an operating shaft therein, a rotor 35 on the shaft at the rear end thereof, a circuit breaker operated by the shaft at the front end thereof and a governor for the circuit breaker between same and said rotor.

40 2. A timer comprising a casing having an enclosed rear end, and a cap on the front end, a plate carrying a fixed and movable contact at the front end of the casing held in place by said cap and a shaft in the casing having a bearing in said cap.

45 3. A timer comprising a casing having an opening in the top, a cover on said opening, an enclosed coil on said cover, a timer plate in the casing, and an angle-shaped conducting member secured to the inside of the cover and connected to the coil at one end and to one of the contacts on the timer plate on the opposite end.

50 5. A timer comprising a casing having an opening in the top, a cover on said opening, an enclosed coil on said cover, a timer plate in the casing, and an angle-shaped conducting member secured to the inside of the cover and connected to the coil at one end and to one of the contacts on the timer plate on the opposite end, said timer plate having an opening adjacent the lower end of said member.

55 6. A timer comprising a casing with a coil on the top thereof, a shaft in the casing, a

circuit breaker plate at the front of the casing, a fixed and a movable contact on said plate and connected to the primary of the coil and a cap over the timer plate, said cap having an opening exposing said contacts. 70

6. A timer comprising a casing having a shaft therein, the front end of the casing being open, an interrupter plate mounted in the front of the casing, a cap for said plate engaging the rim thereof, the cap having an opening adjacent the contacts of the interrupter, a cover engaging the rim of the cap and a retaining member for the cover. 75

7. A timer comprising a casing having a shaft therein, the front end of the casing being open, an interrupter plate mounted in the front of the casing, a cap for said plate engaging the rim thereof, the cap having an opening adjacent the contacts of the interrupter, a cover engaging the rim of the cap and a retaining member for the cover, the shaft being mounted in a bearing at the rear of said casing and in said cap. 80

8. A timer comprising a casing having an opening in the top, a cover on said opening, a coil on the cover, a timer plate in the casing, a conducting member secured to the inside of the cover and connected to the coil at one end and to one of the contacts on the timer plate at the opposite end, said timer plate having an opening adjacent the last-named end of said member. 85

9. A timer comprising a casing having an enclosed rear end, and a cap on the front end, a plate carrying a fixed and movable contact at the front end of the casing held in place by said cap and a shaft in the casing having a bearing in said cap, the latter having an opening adjacent said contacts. 90

10. A timer comprising a casing with a bearing at one end, a shaft in said bearing, a distributor member fixed on said shaft and recessed to receive said bearing, a plate carrying a fixed and a movable contact in said casing and a cover holding said plate in position, said cover having another bearing for said shaft. 105

11. A timer comprising a casing having a bearing, a shaft in said bearing, a distributor member fixed on said shaft and recessed to receive the bearing, a plate carrying a fixed and a movable contact in the casing, a cover for said plate and holding the plate in position, said cover having a second bearing for the shaft, a cam on the shaft to operate the movable contact and a governor on the shaft between said plate and said member. 115

12. A timer comprising a casing having an opening in the top, a cover on said opening, a coil on the cover, a timer plate in the casing carrying a fixed and a movable contact, a member secured to the inside of the cover and connected to the coil on one end, a conductor having connection with said 120

member and leading to one of said contacts, and a screw for attaching said conductor to said member, the plate having an opening exposing said screw.

13. A timer comprising a casing, a shaft in the casing, a circuit breaker plate at the front of the casing, a fixed and a movable contact on said plate and a cover over said plate, the cover having an opening exposing said contacts.

14. A timer comprising a casing with an enclosed rear end, and an inward projecting bearing supported by said end, a cap on the opposite end, a plate carrying a fixed and a movable contact at said opposite end, held

in place by said cap, the latter carrying a second bearing and a shaft in said bearings carrying means to operate the movable contact.

15. A timer comprising a casing with an enclosed rear end, and an inward projecting bearing supported by said end, a cap on the opposite end, a plate carrying a fixed and a movable contact at said opposite end, held in place by said cap, the latter carrying a second bearing and a shaft in said bearings carrying a distributor member and means to operate the movable contact.

In testimony whereof I affix my signature.

JOHN F. MARTIN.
